FIG. 5.

FIG. 4.

INVENTOR.
Charles S. Evans

UNITED STATES PATENT OFFICE.

CHARLES S. EVANS, OF OAKLAND, CALIFORNIA.

PAPER RECEPTACLE.

Application filed December 1, 1922. Serial No. 604,172.

My invention relates to receptacles made from a folded paper blank, and one of the objects of the invention is the provision of a receptacle having a superior means for effecting the closure of the cover flaps. Another object is the provision of a receptacle such as the well known oyster pail in which means are provided for drawing the folded sides together to secure the snug closing of the cover flaps and the consequent bracing of the structure.

My invention possesses other objects and features of advantage, some of which, with the foregoing, will be set forth in the following description of my invention. It is to be understood that I do not limit myself to the showing made by the said description as I may adopt variant forms of my invention within the scope of the claims.

Broadly considered my invention comprises a receptacle formed from a single blank of paper, by folding so that the material lying between the adjacent lateral sides of the folded receptacle is turned back in two overlapping folds on each of its two opposite sides. These overlapping folds which are each of double thickness not only stiffen the receptacle, but form the mounting for the wire bail or handle. The blank of paper is of such shape that when it is folded to form the receptacle, a cover flap is formed on each upper edge and a tab on the outer layer of each overlapping fold extends above the upper edge of the receptacle a distance equal to one-half of the width of the receptacle at the top between the tabs. When the blank is folded the two tabs on each side are contiguous and coincident as to outline.

Preferably a flexible metal tongue is secured to the outer of one of the pairs of tabs while an elongated aperture to receive the tongue is formed in both the opposite tabs. When the tabs are bent toward each other over the closed cover flaps, and the tongue passed thru the opposite apertured tabs and bent back, the effect is to draw the opposite sides of the receptacle strongly together upon the enclosed cover flaps, producing a very snug and neat closure, and a rigid strong package.

Fig. 1 is a plan view of the paper blank from which my receptacle is formed. Fig. 2 is a perspective view of the open receptacle, and Fig. 3 is a similar view of the closed receptacle. Figs. 4 and 5 are each a per-

spective of a receptacle showing a modified form of fastener. Fig. 6 is a plan view of a modified form of blank.

Referring first to Fig. 1 the blank comprises a bottom area 2, side wall areas 3, and end wall areas 4. End wall cover flaps 6 and side wall cover flaps 7 extend integrally from the end and side wall areas respectively. The areas 8-9 lying between each lateral wall and adjacent lateral end walls are creased on the diagonal line 10 when the receptacle is formed, resulting as shown in Fig. 2, in overlapping folds.

Extending from each area 8-9 on one side are tabs 11 and 12 respectively of a length substantially equal to one-half the distance between the upper edges of the side walls of the completed receptacle. These tabs are both provided with apertures 13. Similarly extending from the areas 8-9 on the other side are tabs 14 and 15, to one of which, 15, a flexible metallic tongue 17 is secured by any suitable means.

The position of the tabs and the proportions of the blank are such that when the blank is folded into the form shown in Fig. 2, the apertured tabs 11 and 12 lie coincidentally, the apertures registering; while on the opposite side the two tabs 14 and 15 are similarly positioned, the outer one 15 bearing the flexible tongue 17. It is to be noted that in each case, the tab extends upwardly from the outer layer of the folded areas 8-9, with which it is associated. A bail or handle 18 is secured in the lapping folds in the usual way.

With the closing of the cover flaps 6 and 7, the tabs may be bent toward each other to permit the tongue 17 to be passed thru the aperture 13 in both the opposite tabs. The bending back of the tongue tends to draw the tabs together and since the tabs are integral extensions of the outer layers of the folds on the side walls, such folds are drawn snugly in against the cover flaps making not only an exceedingly tight closure, but one of trim appearance, since the gapping of the sides is prevented. The drawing in of the sides into firm engagement with the cover flaps in the manner explained also results in a package of greater rigidity and strength. It will be observed that the companion tab to the tab bearing the tongue, that is tab 14, is not assigned any particular function in the foregoing. The tab is how-

ever smoothed down flat under the overlying tongued tab 15, and tends, when the outer tab is drawn down tightly over it, to pull in the connected fold and secure it firmly 5 against the cover flaps. If desired the tongue may be secured to both tabs 14 and 15. However it is found that the holes will pull out of both apertured tabs about as easily as the tongue will tear away from the 10 single tab.

Referring now to Fig. 4: If desired, both pairs of tabs 21 and 22 may be apertured in the blank, and subsequent to the folding of the blank, a flexible tongue 23 looped thru 15 one pair of tabs. This arrangement is mechanically desirable since it results in an evenly distributed pull by the bent tongue on all four of the tabs. If commercially practicable, the half bent tongues may be 20 supplied loose and inserted in the apertured tabs and bent flat at the time of closing the receptacle.

The second fastener is however open to obvious objections, and therefore I prefer 25 in many respects the structure shown in Fig. 5, in which both pairs of tabs are apertured and the tongue 26 is secured to the upper cover flap 7 in a central position, and with the ends slightly bent up as shown, so as to 30 be readily engageable in the apertures of the tabs. Because of the connection of the two pairs of tabs by means also connected to the outer cover flap, this receptacle is particularly rigid when closed.

If desired, the blank, as shown in Fig. 6, 35 may be formed with tabs 28 and 29 extending from one of the areas 8 and 9 respectively on each side, each pair of tabs being symmetrical with respect to the diagonal 40 crease line 10.

I claim:

1. A receptacle having oppositely disposed sides in each of which a fold comprising two layers of material extends from both 45 lateral edges to lap at the center of the upper edge, the outer layer only of each fold on each side being integrally extended in coincident separate tabs attached only at their bases, and means separately stressing

each of said oppositely disposed separate 50 tabs for drawing together and securing the sides of the receptacle.

2. A blank for a paper receptacle comprising a rectangular area for the bottom, areas for the sides, areas between the side 55 areas to be folded against oppositely disposed sides when the receptacle is formed, an area for a cover flap adjoining each side area, and oppositely disposed integral extensions from said folded areas to form tabs 60 attached only at their bases wherewith the sides of the receptacle may be drawn snugly together and the cover flaps secured in closed position.

3. A blank for a paper receptacle comprising a rectangular area for the bottom, areas for the sides, areas between the side areas to be folded against oppositely disposed sides when the receptacle is formed, an area for a cover flap adjoining each side area, and integral extensions from said folded areas substantially one-half the width of the bottom area in length and forming tabs attached only at their bases, wherewith the sides of the receptacle may be drawn together and 70 the cover flaps secured in closed position.

4. A paper receptacle having opposite sides each provided with a tab, a pair of inner cover flaps, a pair of outer cover flaps, and a flexible tongue attached intermediate 80 its ends to one of the cover flaps and engageable in the tabs.

5. A paper receptacle having oppositely disposed sides comprising lapping folds, the outer layers of the folds on each side being 85 integrally extended and apertured to form separate twin tabs having coincident slots, a pair of inner cover flaps, a pair of outer cover flaps foldable across the inner flaps, and a flexible tongue attached intermediate 90 its ends to one of the cover flaps and engageable in the slots of each pair of tabs whereby the sides of the receptacle may be drawn snugly together and the cover flaps secured in closed position.

In testimony whereof, I have hereunto set my hand.

CHARLES S. EVANS.
